UNITED STATES PATENT OFFICE

152,062

DESIGN FOR AN ELECTRIC HEATER CASING

William W. Chatfield, Huntington, W. Va., assignor to Armstrong Products Corporation, Huntington, W. Va., a corporation of West Virginia

Application July 1, 1947, Serial No. 140,038

Term of patent 14 years

(Cl. D81—10)

To all whom it may concern:

Be it known that I, William W. Chatfield, a citizen of the United States, residing at Huntington, in the county of Cabell and State of West Virginia, having invented a new, original, and ornamental Design for an Electric Heater Casing, of which the following is a specification, reference being had to the accompanying drawings, forming a part thereof.

In the drawings:

Fig. 1 is a perspective view of an electric heater casing embodying my new design; and Figs. 2, 3 and 4 are plan, side elevation, and front elevation views respectively.

I claim:

The ornamental design for an electric heater casing, as shown.

WILLIAM W. CHATFIELD.
